UNITED STATES PATENT OFFICE.

HEINRICH DREWELL, OF HANOVER, GERMANY.

MECHANISM FOR PERFORATING THE OPERATING-BANDS OF AUTOMATIC TYPE-SETTING MACHINES.

No. 866,343.

Specification of Letters Patent.

Patented Sept. 17, 1907.

Application filed August 25, 1906. Serial No. 332,089.

To all whom it may concern:

Be it known that I, HEINRICH DREWELL, engineer, a subject of the German Emperor, residing at Hanover, 26 Dieterichstrasse, Germany, have invented 5 certain new and useful Improvements in Mechanism for Perforating the Operating Bands of Automatic Type-Setting Machines; and I do hereby declare the following to be a full, clear, and exact description of the invention, such as will enable others skilled in the 10 art to which it appertains to make and use the same.

This invention relates to mechanism for perforating the operating bands of automatic type setting machines and compared to devices of the same kind at present known is distinguished by its simplicity and efficiency.

15 In order to attain high speed the apparatus constructed in accordance with this invention is provided with means for connecting the different stages in the operation of preparing a group of perforations in the band and thus execute them quickly. The stages in 20 question are as follows:—1. The release of the perforating punch which is effected by the depression of a key. 2. The perforation of the paper. 3. The withdrawal of the punch. 4. The advance of the paper. The quick sequence of these steps is obtained in the 25 following manner. By means of keys acting in some wellknown manner on combination mechanism, locking hooks or pawls are withdrawn which release directly or indirectly perforating punches which are in turn controlled by springs, weights or the like and effect 30 the perforation of the paper. The movement of the punches is so arranged as to operate mechanism which causes a spindle to make one revolution, rotation of this spindle during the first half of this revolution causing the withdrawal of the punches from the 35 dies and during the second half of the revolution advancing the paper or other band in which the perforations are made.

The accompanying drawings illustrate diagrammatically the method of carrying out the present invention. 40 Figure 1 is a side elevation partly in section of the whole apparatus, Fig. 2 is a sectional plan on the line 2-2 of Fig. 1. Fig. 3 shows a detail. Fig. 4 shows diagrammatically the arrangement by which one key can act on several punching-dies. Fig. 5 shows in elevation, and partly in section, a modified arrangement of the device shown in Fig. 1. Fig. 6 shows an arrangement for electrically releasing the punching-dies. Fig. 7 shows the arrangement for electrically releasing the key-levers.

50 There are a plurality of punches of which only a single one 1 is shown in the drawings. This punch is carried in a guide 2 and in operation enters the die 3. The punch is operated by a two-armed lever 4 pivoted on a pin 5 and controlled by a spring 6 so arranged 55 that as soon as the lower end 7 of the lever has been

released from the retaining catch 8 the punch will perforate the band passing between it and the die 3. The number of punches, levers and catches therefore corresponds to the number of perforations which are employed to give the necessary combinations for 60 producing the characters and operating the type setting machine.

The release of the locking catches 8 is effected by depression of a plurality of keys 9 each of which acts on a number of combination bars 10. The latter are secured to levers pivoted at 11 and by means of the arm 12, rod 13 and spring controlled hook or catch 14 the depression of a key causes the locking catches 8 to be drawn clear of the ends of the levers 7 so as to release the latter. As a result the lever 4 is so moved by the 70 spring 6 that its upper end which enters into the hooked or recessed part 37 of the punch 1 causes this punch to perforate the paper 36. Simultaneously the lower end 7 of the lever 4 pushes back the catch 14 by means of the pin 15 and at the same time the lever 4 pushes back 75 the bar 16. The latter is mounted on two arms 18 which pivot about a spindle 17. On the spindle 17 is also mounted an arm 19 having an inclined or cam face 20 (Fig. 3) against which rests an arm or pawl 21. This pawl 21 is pivotally mounted on a rotatable disk 23 80 carried on a spindle 22 and a spring 24 so acts upon the pawl 21 that when the latter is released owing to the arm 19 being moved away from it the pawl will move into engagement with a ratchet wheel 25 mounted loose on the spindle 22 but constantly rotated in some convenient manner from a source of power. The pawl 21 and ratchet wheel 25 in effect constituting clutch members which when intermittently engaged in the manner described cause the disk 23 and spindle 22 to rotate with the ratchet wheel 25. Mounted on the spindle 22 are 90 a plurality of eccentrics or cams 26 corresponding to the levers 4 and punches 1. On rotation of the spindle 22 each eccentric 26 bears against the corresponding lever 4 after a punch has been operated and returns the punch and lever to their normal positions where they are held 95 by the catch 8 engaging with the end 7 of the lever. After every complete revolution of the spindle 22 the pawl 21 comes into engagement with the cam face 20 on the arm 19 and is thereby disengaged from the ratchet wheel 25 so that while the latter continues to rotate, the spindle 22 and eccentrics 26 come to a standstill. It will thus be seen that at each depression of a key the number of levers corresponding to the desired combinations are released and cause the punches controlled by them to make the perforations forming the 105 combination in the band. The release of the levers in the first instance having caused engagement of the clutch members the mechanism thus brought into operation finally returns the levers to their positions of rest owing to a single revolution of the eccentrics 26. 110

On the spindle 22 is mounted another and larger eccentric 27 provided with a strap 28 and rod 29 which connects the eccentric to the oscillating arm 30. This arm 30 is loosely mounted on the spindle 31 of the feed roller 32 and is provided with a pawl 33 which engages with a ratchet wheel 34 mounted on the spindle 31. At each revolution of the spindle 22 the motion imparted by the eccentric 27 to the oscillating arm 30 causes the ratchet wheel 34 to be advanced to an extent determined by the throw of the eccentric 27. The ratchet wheel is held in the position to which it is moved by a pawl 35 and thus prevented from moving back again. The roller 32 rotates with the ratchet wheel 34 and thus causes an advance to the desired extent of the band 36 which passes over the roller. The eccentrics 26 and 27 are so disposed relatively that during the first half of the revolution of the spindle 22 the levers 4 are returned to their normal positions by the eccentrics 26 and consequently the punches removed from the band 36 while during the second half of the revolution of the spindle 22 the band is advanced by the movement of the eccentric 27 in the manner described.

In Fig. 4, 10 are the combination-rails which turn on arms on a common axis 11. The rails 10 carry each an arm 12 which engage the lower ends of the drawing-rod 13. The number of combination-rails is equal to the number of punching-dies used, but may otherwise be of any desired number, as that of the punching-dies. The keys 9 press on the combination-rails by means of special projections or teeth, similar to the teeth 46 of the key-lever 44 in Fig. 7. The number and position of these teeth on a key-lever determines in any desired manner the number of individual punching-dies which are to be released by the key.

Fig. 5 shows a special form of the arrangement shown in Fig. 1, in which the lever 4' has a separate lever-arm for each function. In this case the pawl 8' engages the arm 7'. On an arm 4' is arranged a draw-spring 6' which forces the punching-die through the paper. An arm 4b' engages the hook 37' of the punching-die 1'. The cam 26' acts on a roller which is rotatably connected with a' arm 7" of the lever 4', for the purpose of returning the lever 4 after each punching operation to its normal position of rest. The operation of the individual parts is otherwise the same as in Fig. 1.

Figs. 6 and 7 show diagrammatically different forms of releasing the punching devices by means of an electrical release of the same.

The parts 7", 8", 14" and 13" correspond to the parts 7', 8', 14 and 13 in Fig. 5. On the drawing-rod 13", which actuates the hook 14", acts an arm of the angle-lever 40, the other arm of which carries the armature 41 of an electromagnet 42. The electromagnets 42 are, for convenience sake, arranged in several rows, one above the other, and located at both sides of the row of draw-bars 13".

The actuation of the electromagnets 42 by a key system is shown diagrammatically in Fig. 7. The key-levers 44 are rotatably supported on a common axis 45. They carry projections 46 and act by the same on one or several of the cross-levers 47. The cross-levers 47 are rotated on the axis 48 and are pressed by springs 49 against the key-levers 44, thereby holding the same in a position of rest. The levers 47 carry on their free ends projections 50, which, during the depression of the levers, form contact with the springs 51. The latter are connected by clamps 52 with an isolated base 53.

The electrical connections of the electromagnets 42 are as follows: From one pole of the source of current 55 the contact-wire 56 is connected with the axis 48 of the lever 47. From the other pole of the source of current 55 a branch-circuit 58 leads to the electromagnets 42. These are connected by the conducting-wires 57 with the clamps 52 and the contact-springs 51. This arrangement operates as follows: By depressing the key-lever 44 some levers 47 are placed in contact, by the teeth 46, with the contact-springs 51. By this motion the circuit of one or more of the electromagnets 42 is closed and the electromagnets excited. In consequence thereof they lift their armatures 41 (Fig. 6) on which the angular levers 40 and the draw-rods 13" are secured, so that the punching-dies are released.

The number of the electromagnets 42 is equal to the number of the cross-levers 47. Otherwise the two parts can be of any desired number. Which electromagnets 85 act simultaneously on depression of a special key depends upon the number and the arrangement of the teeth 46 on the key-levers 44. These teeth have to be arranged in accordance with the object of the entire apparatus. Their disposition does not influence the remaining parts of the apparatus. However, this electrical key system is not a part of the invention.

The coupling or clutch for connecting the spindle 22 to the ratchet wheel 25 or source of power may be of any known type the pawl and ratchet being above described by way of example. The above mentioned apparatus for perforating the operating bands for automatic type setting machines may if desired be combined with other auxiliary devices used in similar apparatus as for example typewriting machines measuring and justifying devices and the like.

Having now particularly described and ascertained the nature of my said invention and in what manner the same is to be performed I declare that what I claim is:

1. In mechanism for perforating the operating bands of automatic type setting machines, the combination of a plurality of keys, a plurality of punches, means tending to operate these punches, means for retaining the punches in their inoperative positions, a plurality of dies corresponding to the punches, punch releasing mechanism controlled by the keys, a source of power, mechanism for returning the punches after operation to their inoperative positions, mechanism for imparting motion to the band, a clutch for connecting these mechanisms to the source of power and a clutch controlling device actuated by the punch operating mechanisms as set forth.

2. In mechanism for perforating the operating bands of automatic type setting machines the combination of a plurality of keys, a plurality of punches, means tending to operate these punches, a plurality of catch devices retaining the punches in their inoperative positions, a plurality of dies corresponding to the punches, mechanism controlled by the keys for operating the catch devices and releasing the punches, a source of power, mechanism for returning the punches after operation to their inoperative positions, mechanism for imparting motion to the band, a clutch for connecting these mechanisms to the source of power, and a clutch controlling device actuated by the punch operating mechanisms as set forth.

3. In mechanism for perforating the operating bands of automatic type setting machines the combination of a plurality of keys, a plurality of punches, means tending to operate these punches, a plurality of catch devices retaining the punches in their inoperative positions, a plurality of dies corresponding to the punches, mechanism con-

motion of the eccentric, a clutch member loosely mounted on the spindle and connected to the source of power, a clutch member fast on the spindle and a pivoted lever connected to a cam member normally operating to maintain the clutch members disengaged but actuated by the punch operating levers when released so as to allow the engagement of the clutch members as set forth.

23. In mechanism for perforating the operating bands of automatic type setting machines the combination of a plurality of keys, a plurality of punches, a plurality of punch operating levers, means tending to move these levers and operate the punches, a plurality of catch devices retaining the levers in their inoperative positions, a plurality of dies corresponding to the punches, a feed roller for the paper band, a ratchet feed device for the feed roller, mechanism controlled by the keys for operating the catch devices and releasing the punch operating levers, a source of power, a spindle carrying a plurality of rotary members for returning the punch operating levers after operation to their inoperative positions, an eccentric on this spindle, a strap and rod connecting this eccentric to the ratchet feed device of the band feed roller and imparting thereto the motion of the eccentric, a clutch member loosely mounted on the spindle and connected to the source of power, a clutch member fast on the spindle and a pivoted cam member normally operating to maintain the clutch members disengaged but actuated by the punch operating levers when released so as to allow the engagement of the clutch members as set forth.

24. In mechanism for perforating the operating bands 30 of automatic type setting machines the combination of a plurality of keys, a plurality of punches, guides for the punches, a plurality of punch operating levers, springs tending to move these levers and operate the punches, a plurality of catch devices retaining the levers in their inoperative positions, a plurality of dies corresponding to the punches, a feed roller for the paper band, a ratchet feed device for the feed roller, spring controlled lever and link mechanism actuated by the keys for operating the catch devices and releasing the punch operating levers, a 40 source of power, a spindle carrying a plurality of rotary members for returning the punch operating levers after operation to their inoperative positions, a separate rotary member on this spindle, an operative connection between this rotary member and the ratchet feed device of the 45 band feed roller, a clutch for connecting this spindle to the source of power and a pivoted lever connected to a cam member normally operating to maintain the clutch members disengaged but actuated by the punch operating levers when released so as to allow the engagement of the 50 clutch members as set forth.

In testimony, that I claim the foregoing as my invention, I have signed my name in presence of two subscribing witnesses.

HEINRICH DREWEIL.
